Alfred C. Gilmore, Lyndhurst, N. J., and Stanley J. Harazim, New York, N. Y., assignors to Bell Telephone Laboratories, Incorporated, New York, N. Y., a corporation of New York

Application September 7, 1950, Serial No. 12,096

Term of patent 14 years

(Cl. D26—14)

To all whom it may concern:

Be it known that we, Alfred C. Gilmore and Stanley J. Harazim, citizens of the United States, residing at Lyndhurst, in the county of Bergen and State of New Jersey; and at New York, in the county of New York and State of New York, respectively, have invented a new, original, and ornamental Design for a Telephone Operator Desk, of which the following is a specification, reference being had to the accompanying drawing, forming a part thereof, in which:

Fig. 1 is a view, in perspective, of a telephone operator desk, showing our new design;

Fig. 2 is a top plan view thereof;

Fig. 3 is a front elevational view thereof;

Fig. 4 is a side elevational view thereof as seen from the right in Fig. 1; and

Fig. 5 is a side elevational view thereof as seen from the left in Fig. 1.

We claim:

The ornamental design for a telephone operator desk, as shown.

ALFRED C. GILMORE.
STANLEY J. HARAZIM.
